Inventor
By Atty's Earle Seymour

UNITED STATES PATENT OFFICE.

GEORGE E. ALBEE, OF NEW HAVEN, CONNECTICUT.

FORE-AND-AFT-RIGGED VESSEL.

SPECIFICATION forming part of Letters Patent No. 625,132, dated May 16, 1899.

Application filed October 17, 1898. Serial No. 693,846. (No model.)

To all whom it may concern:

Be it known that I, GEORGE E. ALBEE, of New Haven, in the county of New Haven and State of Connecticut, have invented a new 5 Improvement in Fore-and-Aft-Rigged Vessels; and I do hereby declare the following, when taken in connection with the accompanying drawing and the letters of reference marked thereon, to be a full, clear, and exact 10 description of the same, and which said drawing constitutes part of this specification, and represents a side view of a two-masted schooner embodying my invention.

This invention relates to an improvement 15 in the rigging of fore-and-aft vessels having two or more masts.

As is well known, when sailing the outer ends of the gaffs of the foresails sag to leeward, so that a large proportion of the force 20 of the wind is lost, and this sagging not only prevents the lower sails, but also the gaff-topsails, from properly drawing.

The object of this invention is to prevent 25 the sagging to leeward of the outer ends of the gaffs of vessels; and it consists in securing to the outer ends of the gaffs a rope which extends through a pulley or eye fixed to the head of the mast next aft of the mast carrying the gaff or to some point in the rigging and from 30 thence to the deck, whereby the peak may be hauled to windward into its proper position.

For convenience of illustration I have shown 35 my invention as applied to a two-masted schooner; but it is apparent that it is equally applicable for fore-and-aft-rigged vessels having a greater number of masts.

The sails and rigging of the vessel as herein shown are of usual arrangement, and except as necessary will not be specifically referred to.

To the outer end A of the gaff B of the fore-sail C, I secure what I will hereinafter term a "gaff trimming-line" D, which is rove through 40 a pulley-block E, or it may be an eye, ring, or similar device, secured near the head of the mainmast F below the spring-stay G and at a point in line with or above and thence to the deck, where it may be made fast in the usual manner.

If the vessel has more than two masts, it will be understood that the respective rings 50 or eyes will be secured to the mast or portion of the rigging next aft of the gaff to which the trimming-line is secured.

Instead of making the block or eye fast to the mast it may be connected with the spring-stay, shroud, or other convenient point in the rigging, it only being essential that the block or eye shall be in position so that the gaff may be hauled to windward.

With a gaff trimming-line as herein shown 60 the upper part of the foresail may be trimmed as well as the gaff-topsail H or other sails which are secured or sheeted to the gaff, and so that the peak may be hauled to windward and the efficiency of the sails increased. 65

It is apparent that instead of passing the free end of the gaff trimming-line to the deck it may be secured to the masthead or at other convenient points in the rigging, as on long tacks this sheet would not have to be adjusted, but if need be is readily reached from the masthead. Furthermore, instead of making the end of the gaff trimming-line fast to the outer end of the gaff the sheet may be secured by a bight around the end of the gaff 70 and the free end extended to the deck, so that it may be used as a downhaul for the gaff. 75

Having fully described my invention, what I claim as new, and desire to secure by Letters Patent, is—

In a fore-and-aft-rigged vessel, the combination with the gaff, of a gaff trimming-line secured to the outer end of said gaff, said gaff trimming-line extending to a point aft of the outer end of and in line with or above said 85 gaff and means for securing said line, substantially as described.

In testimony whereof I have signed this specification in the presence of two subscribing witnesses.

GEORGE E. ALBEE.
